UNITED STATES PATENT OFFICE.

CHARLEY E. MATTISON, OF DE RIDDER, LOUISIANA.

RAIL-MOISTENER.

1,277,236.

Specification of Letters Patent. Patented Aug. 27, 1918.

Application filed June 13, 1918. Serial No. 239,850.

To all whom it may concern:

Be it known that I, CHARLEY E. MATTISON, a citizen of the United States, residing at De Ridder, in the parish of Beauregard 5 and State of Louisiana, have invented a new and useful Rail-Moistener, of which the following is a specification.

The device forming the subject matter of this application is adapted to be used for 10 supplying cool water to the rails of a track, for the purpose of lessening the friction, the structure increasing the mileage which the wheels will run, and serving to cool the rails, thereby reducing heat and causing a 15 train to draw more easily than otherwise would be the case.

The invention aims to provide a structure of the kind mentioned which is of a simple makeup, and capable of being connected to 20 standard parts of a locomotive engine, without working changes therein.

Another object of the invention is to provide a structure of the sort mentioned which takes the water from the tender, as distinguished from the locomotive engine itself, 25 thereby obviating any possibility of interfering with the working of the injector, cool water being supplied to the track.

It is within the province of the disclosure 30 to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within the scope of what is claimed, changes in 40 the precise embodiment of the invention shown can be made without departing from the spirit of the invention.

In the drawings:—

Figure 1 is a side elevation; Fig. 2 is a 45 section on the line 2—2 of Fig. 1.

The numeral 1 marks the tender of a locomotive engine E the tender including a tank 2 and a frame 3 supporting the tank. A pipe 4 communicates with the tank 2 and is 50 provided with a valve 5. The pipe 4 has a lateral branch 6 with which is connected a coupling 7. The parts above alluded to constitute a portion of a known locomotive equipment, and no novelty is claimed for 55 them, saving in so far as they may coöperate

with parts hereinafter described. The coupling 7 is resorted to, and the valve 5 is opened, when it is desired to use water for any purpose, exteriorly of the tender.

In carrying out the present invention, a 60 horizontal pipe 8 is assembled with the lower end of the pipe 4 and extends inwardly, beneath the tank 2, to the frame 3. With the end of the pipe 8 is connected a 65 vertical pipe 9 passing downwardly along the side of the frame 3. The lower end of the pipe 9 is assembled with one end of a horizontal pipe 10 located beneath the frame 3 and connected thereto by brackets 11. The other end of the pipe 10 is closed by a cap 70 50 as shown in Fig. 2. T couplings 12 are interposed in the horizontal pipe 10 and are connected by means of reducers 14 with branch pipes 15 which curve downwardly and discharge at the rear of a brake beam 75 16, in front of the forward wheels 17 of the tender, although, as those skilled in the art will appreciate, the pipes may be located as desired without jeopardizing the utility 80 of the invention, provided that certain features thereof are retained.

The branch pipes 15 are considerably smaller in diameter than is the horizontal pipe 10. The valve 5 is opened, and the water flows downwardly from the tank 2 85 and is discharged through the branch pipes 15, on the rails, for the purpose hereinbefore set forth.

The couplings 7 remain open during the time that the water is flowing from the tank 90 2 through the pipes 15, but the amount of water supplied is so small that the water does not overflow at the couplings 7. The couplings 7 serve to admit air into the pipes 8, 9, 10 and 15, and facilitate the flow of 95 water through the pipes 15. When it is desired to use water at the couplings 7, the valve 5 is opened to full head, or nearly so, the amount of water which trickles through the branch pipes 15 being so small that the 100 supply at the coupling 7 is not diminished materially.

Especial attention is directed to the fact that the water is drawn directly from the tank 2 of the tender 1, and not from some 105 part of the circulatory system nearer to the engine. As a consequence, cool water is always supplied to the rails, and there is no danger that the injector or other parts of the locomotive will be interfered with.

It is to be observed that the device forming the subject matter of this application may be assembled with the tender of a locomotive engine at trifling cost, and it being unnecessary to work any material changes in the make up of the tender, the pipes 8 being coupled merely to the lower ends of the pipe 4 which are a standard part of a locomotive construction.

Having thus described the invention, what is claimed is:—

1. In a device of the class described, a locomotive engine including a tender comprising a tank and a track wheel; a conduit leading directly from the tank of the tender and discharging in a common vertical plane with the wheel; and a valve in the conduit, adjacent the tank, the conduit having a nor-

mally open vent disposed between the valve and the discharge end of the conduit. 20

2. In a device of the class described, a locomotive engine including a tender comprising a frame, a tank on the frame, and a track wheel; a pipe extended transversely of the frame and having one of its ends in direct communication with the tank; and a branch pipe leading from the transverse pipe, the branch pipe discharging in a common plane with the wheel. 25

In testimony that I claim the foregoing as 30 my own I have hereto affixed my signature in the presence of two witnesses.

CHARLEY E. MATTISON.
